UNITED STATES PATENT OFFICE.

ROBERT A. HEGGIE AND EDWARD A. WAGENER, OF ITHACA, NEW YORK.

EAR-RING FASTENER.

SPECIFICATION forming part of Letters Patent No. 249,238, dated November 8, 1881.

Application filed August 8, 1881. (Model.)

To all whom it may concern:

Be it known that we, ROBERT A. HEGGIE and EDWARD A. WAGENER, citizens of the United States, residing at Ithaca, in the county of Tompkins and State of New York, have invented a new and useful Ear-Ring Fastener, of which the following is a specification.

Our joint invention relates to improvements in ear-ring fasteners, the nature and object of which are to attach and secure the ear-ring to the lobe of the ear without piercing the ear; and also to attach and secure the ear-ring to the ear which is pierced, at the same time holding the drop or setting in proper position. We attain these objects by the mechanism illustrated in the accompanying drawings, in which—

Figure 1 represents an enlarged vertical section of the whole of the lower portion of the device. Fig. 2 is a vertical section of the concave disk which clamps upon the lobe of the ear. Fig. 3 is a full-sized drawing of the ear, with the fastener and ear-ring attached. Fig. 4 is an enlarged view of the ear-ring and fastener entire. Fig. 5 represents two different cross-sections of the parts shown in Fig. 1. Fig. 6 is a surface plan of the disk represented in Fig. 2, showing the roughened concave surface.

Similar letters refer to similar parts throughout the several views.

The manufacture of this invention consists of a bent-wire arm, *e*, as shown in Fig. 4, terminating in a disk, *f*, and attached to the bent-wire arm *d* by a rivet-joint, *c*, which bent-wire arm *d* also terminates in a disk, *g*. The barrel *b*, with a slotted end, turns about a part of the bent-wire arm *e* and allows the bent-wire arm *d* to assume the position of the dotted line *d'*, and the barrel *b*, by being turned to its proper position, clamps the disks *f* *g* securely to the lobe of the ear. The flange *i* is for

the purpose of attaching the setting or ornament. The eye *a* is used for attaching a pendant and for turning the barrel *b*. The slotted end of the barrel *b*, between the slot *j* and the eye *a*, is wedge-shaped, so as to press outward against the lower end of the bent-wire arm *d*, below the rivet-joint *c*, working in the manner of an eccentric, thus forcing the upper or disk end of the bent-wire arm *d* toward the upper or disk end of the bent-wire arm *e* and holding it securely in its place. The barrel *b*, at the end next the arm *e*, is notched, so that the barrel *b* cannot be turned in either direction farther than a quarter of a circle. The metal pin *h*, fastened in the inner center of the concave disk *f*, passes through the ear which is pierced, meeting a shallow hole in the inner center of the concave disk *g*, thus more securely fastening the ornament to the ear and retaining it in proper position by the aid of the disks *f* *g*, which clamp upon either side of the lobe of the ear.

What we claim as our invention, and desire to secure by Letters Patent, is—

1. In an ear-ring, the barrel *b*, adapted to turn, and having an eccentric and slotted end next the bent-wire arm *d*, as described and shown.
2. In an ear-ring, the barrel *b*, notched at one end, as set forth.
3. The concave disk *f*, adapted to hold in position a removable metal pin, *h*, in combination with the concave disk *g*, provided with a shallow hole in its inner center, adapted to receive the end of the pin, as herein described and shown.

ROBERT A. HEGGIE.
EDWARD A. WAGENER.
